WATER HEATER AND CABINET CONSTRUCTION

Albert J. Lampert, Walnut, and John J. Carlson, South Gate, Calif., assignors to Rheem Manufacturing Company, Richmond, Calif., a corporation of California

Application February 10, 1950, Serial No. 143,412

2 Claims. (Cl. 122—13)

Our invention relates to storage-type hot water heaters and has particular reference to the details of construction of a cabinet of what is known as a table top water heater, i. e., a water heater having a flat top substantially at table height.

Such water heaters are usually formed with a rectangular or square cabinet so that they blend into and become a part of a kitchen cabinet structure. In such event, it is necessary that the back of the cabinet of the water heater fit flush against the wall of the room in which the heater is placed, thereby rendering access to supply and delivery pipes, gas pipes, and/or electrical conduits exceedingly awkward and difficult.

It is one of the objects of our invention to provide a cabinet having one or more channels in the back thereof to permit installation flush against a wall and having a removable top to permit easy access to the connecting pipes and conduits while the cabinet rests flush against the wall.

It is a further object of our invention to provide a cabinet construction wherein the top is readily removable by sliding horizontally to permit ready and easy access to supply pipes and conduits either for purposes of repair or installation.

In all storage-type water heaters some access is necessary to the heater tank in order to properly maintain and operate the water heater.

Prior heaters have usually been provided with a hinged door through one of the panels of the cover, preferably the front panel thereof, so that the water heater can fit into a recess if desired. The panels of the cabinet are usually formed for the sake of economy of relatively light-gauge material and hinging doors to such light-gauge material but presents production difficulties and frequently results in failure during the use because the light-gauge material will not adequately support the door.

We have designed a table-top water heater having access apertures in the front thereof and a false panel adapted to cover the front of the water heater in order to completely conceal the access apertures, which said false panel is easily removable and is held in place by means of resilient spring clips.

Other and further objects and advantages will become apparent from the drawings and the specifications relative thereto.

In the drawings:

Figure 1 is a perspective view taken from the rear of a table top water heater embodying the principles of our invention.

Figure 2 is a top plan view having the top panel and insulation removed for the sake of clarity.

Figure 3 is a sectional view taken on line 3—3 of Figure 2.

Figure 4 is an enlarged fragmentary sectional view taken on line 4—4 of Figure 3.

Referring more particularly to the drawings, we have illustrated a water heater having a base 10, side panels

2

11 and 12, front panel 13 and a back panel 14 assembled into a substantially rectangular box-like structure adapted to contain a storage tank 15, and having insulation 16 contained therein between the panels and the storage tank 15.

The base 10 comprises a plurality of channel members such as 18 and 19 formed in a substantially rectangular shape and having a base plate 20 resting thereon, upon which the tank 15 is adapted to rest.

10 The side panels are each formed with an inturned flange 22 along the rear vertical edge. The back panel 14 is secured thereto by means of any suitable fastening device such as sheet metal screws or bolts 23, or may be spot welded if desired.

15 The back panel 14 is formed with one or more external vertical grooves or channels 25, which have direct vertical access to the floor on which the heater rests. In this way water pipes 26 and 27, which extend vertically upward from the floor, are automatically accommodated

20 when the heater is moved horizontally over the floor until the panel 14 is flush against a wall. Without the channels 25, the panel 14 could not be positioned against the wall; and if the pipes 26 and 27 were to be accommodated within the panel 14, it would be necessary to lift the heater up and over the ends of the pipes before lowering it down with the panel 14 against the wall; this would be an extremely difficult installation job.

25 A retainer stiffener plate 28 is secured in a horizontal position to the upper edge of the panel 14 by means of a flange 29 and sheet metal screws or bolts 30. The retainer 28 acts to retain the insulation 16 in place and also to stiffen the panel 14.

30 The upper edge of each of the side panels 11 and 12 is formed with inturned flanges such as 33 and have an upwardly and outwardly turned lip 34 to define a channel.

35 A removable top 35 having depending peripheral flanges 36 is adapted to enclose the top of the water heater. The depending peripheral flanges 36 are formed with inwardly turned flanges 37 adapted, at the sides, to slidably engage the channels defined by the flanges 33 and the lip 34, so that the top 35 after installation of the heater and connection of the water pipe and other conduit, can be slid into place into abutment against the wall to make a completely enclosed unit.

40 It will be noted from Figure 4 that the top 35 has an overhanging lip 35a. A bracket 35b is secured to the return flange of such overhanging lip by such suitable means as spot welding. The bracket 35b is then removably secured to the front panel 13 by sheet metal screw 35c to securely retain the top in place.

45 The water tank 15 is formed with a drain valve 40 and if electric may be provided with other control and regulating devices as heating elements and control switches 41. The heating elements (inside the tank) are connected to an electrical power source by wires 41a, connected through conduit 41b and junction box 41c.

50 The front panel 13 is formed with an aperture 42 to permit access to the drain valve 40 and a similar aperture to permit access to the controls 41. The panel 13 is also formed with relatively smaller apertures 44 spaced and positioned as may be desired and adapted to receive in cooperating resilient spring 55 slips 45.

55 A false front panel 46 is adapted to overlie the panel 13 to cover the aperture 42, the aperture for access of controls 41 and the bracket 35b and screw 35c and is secured in place by means of the resilient clips 45 which are secured thereto by means of spot welding or other suitable means. It is therefore apparent that a neat-appearing, substantial front is provided which is readily re-

movable for access to the controls or other maintenance equipment of the water storage tank.

It is also readily apparent that the objectives of the invention as above described have been accomplished in that with the top 35 removed, the balance of the assembly can be pushed back into abutment against a wall, permitting the conduits 26 and 27 to pass upwardly through the grooves or channels 25 so that connection thereof to the water tank is relatively simple, and that the connecting pipe and other conduits may be readily hidden from view by sliding the top 35 into position.

We contemplate the use of such insulation 16 as fibre glass which will retain itself in position even around the access apertures such as 42. In the event other types of insulation are used some retainer wall will be necessary to prevent spillage of the material from such access openings.

Whereas the drawings illustrate and the specifications describe a water heater adapted for use with electrical energy to heat the water, the principles of our invention can be adapted and applied equally well to gas fired water heaters. The principal feature of our invention as we conceive it is the combination of a water heater and cabinet construction having a cabinet substantially rectangular in shape adapted for installation flush against a wall and being provided with vertical channels in the back panel thereof to permit the upward passage of supply conduits for making necessary connections in the top and a slidably removable top panel adapted to be easily removed for access to the interior of the cabinet in order to make the necessary connections. Such an invention is equally applicable to both electrical and gas fired water heaters.

While we have herein shown and described our invention in what we have conceived to be the most practical and preferred embodiment, it is recognized that departures may be made therefrom within the scope of our invention, which is not to be limited to the details disclosed disclosed herein, but is to be accorded the full scope of the claims so as to embrace any and all equivalent devices.

Having described our invention, what we claim as new and desire to secure by Letters Patent is:

1. A cabinet adapted to be placed on a floor flush against the wall of a room and to contain a household appliance, said cabinet having a substantially flat back panel for flush installation against said wall, the exterior surface

of said panel being formed with at least one vertical channel or groove having direct vertical access to the floor and adapted to receive service conduits for the appliance, a removable, substantially flat top on said cabinet, said top being disposed in a horizontal plane substantially above said appliance and substantially above the top edge of said back panel whereby said conduits may be disposed within said channel and underneath said top in the region between said top and said appliance.

- 10 2. A water tank cabinet adapted to be placed on a floor flush against the wall of a room and to contain a water storage tank, said cabinet having a substantially flat back panel for installation flush against said wall, the upper edge of said panel lying in a plane substantially even with the top of said tank, the exterior of said panel being formed with at least one vertical channel or groove extending the full height of said panel and adapted to receive a water pipe connectible to said tank, a substantially flat top for said cabinet removably mounted thereon, the under surface of said top being disposed substantially above the top of said tank and the upper edge of said back panel, thereby providing a region through which said pipe may be led in communication from the top of said channel horizontally to said tank, and means removably securing said top to said cabinet.
